DOOR ACTUATED RECIPROCATING SIGNAL
FOR MAILBOXES

Raymond L. Fagner, Burnettsville, Ind.

Application May 8, 1948, Serial No. 25,890

2 Claims. (Cl. 232—35)

1

This invention relates to improvements in rural mail boxes. One object is to provide a rural mail box having a flag signal that is automatically moved from raised position to lowered position when the mail box door is opened thus notifying the box owner that the mail left therein for the postman-collector has been removed by him and that he has delivered additional mail, if any. After the mail left by the postman-collector has been removed by the box owner the flag signal is left in lowered position unless additional mail has been deposited in the box for collection, whereupon it is raised again.

A further object is to provide a rural mail box having signalling means that are positive and efficient in operation, simple in construction, inexpensive to manufacture and durable in use as well as attractive in appearance. A still further object is to provide a rural mail box having a flag signal movable from raised to lowered position by opening of the box door wherein the movable parts are designed for but slight movement so that wear and friction are reduced to the minimum and a substantially weather-resistant structure provided.

Other objects, novel features and advantages of arrangement, construction and design comprehended by the invention are hereinafter more fully pointed out or made apparent from the following description of a preferred embodiment as illustrated in the accompanying drawing wherein like reference characters denote corresponding parts throughout.

In the drawing:

Fig. 1 is a front or face view of the mail box in closed position.

Fig. 2 is a side view of the mail box shown in Fig. 1, two positions of the flag signal being shown.

Fig. 3 is a side view of the mail box, partly in section, the box here being in open position and the flag signal lowered.

Fig. 4 is an enlarged horizontal cross sectional view through a portion of the box, taken on the line 4—4 of Fig. 3, and,

Fig. 5 is a vertical cross sectional view, enlarged, taken on the line 5—5 of Fig. 3.

The reference numeral 1 denotes the body of the box arranged upon the conventional post 1a, open at the front end, to which the door 2 is secured upon hinge pin 3, a resilient latch member 4 secured to the top of the door cooperating with a similar latch member 5 secured to the top of the box to yieldingly retain the door in closed position. The hinge pin 3 extends very slightly

5 beyond one of the box flat vertical side walls 3a and has pivotally arranged thereupon at one end slightly spaced from the box wall the approximately triangular casting 6, the apex of this triangular piece receiving the pin 3, two of the sides of the triangular piece 6 being at right angles to each other, the third side including a segmental portion 7 struck from the pivotal point as a center, the ends of the segment defined by straight shoulders 8, 9 positioned at right angles to each other. The casting 6 is formed with an angular lip or extension 10 bridging the space between the casting and door 2 and secured to the latter so that movement of the door upon its hinge pin through a 90 degree arc also moves the casting in like manner.

Secured to one side wall of the body 1 is a guide bracket 11 and below the same in a straight line are the similar spaced guide brackets 12, 13 also secured to the side wall, said brackets receiving the vertically adjustable flag signal 14 having the head 15 and the outwardly turned heel 16, the elongated shank of said signal being flat and one edge thereof formed with the similar spaced notches 17, 18, said signal when in lowermost position having its head 15 in engagement with the bracket 11 thus effectually preventing the signal from dropping through the brackets to the ground while the heel 16 prevents the manual withdrawal of the signal from the brackets in the opposite direction as said heel comes in engagement with the bracket 13.

35 A slide latch 19 formed of two spaced parallel strips 20, 21 secured together is slidably received between the guide brackets 12, 13 and receives between its strips the shank of the flag signal 14. A dog 22 connecting said strips is shaped complementary to the notches 17, 18 and in the lowered position of the flag signal may be caused by movement of the slide latch to enter or leave the notch 17 and in the raised position of the flag signal to place the dog and notch in line to move the dog into or out of the notch 18 and when in engagement with the latter notch serves to retain the signal in raised position. Carried at the forward end of the slide latch between its strips upon a pin 23 is a roller 24 that rides over the segmental portion 7 of the casting 6 and in one position thereof abuts the shoulder 9 and in the opposite position of the casting abuts the shoulder 8. In Fig. 2 the roller 24 is shown in engagement with the shoulder 8 of the casting, the door 2 is shut and the said shoulder has moved the latch rearwardly to cause the dog 22 to enter the notch 18 thus retaining the flag in raised

55

position. When the door is opened the shoulder 8 will move away from the roller which will move freely over the segmental edge 1 but just before the door assumes its wide open position the shoulder 9 will engage the roller and move the latch sufficiently to disengage the dog from the notch 18 permitting the signal to drop by gravity to lowered position thus indicating that the contents of the mail box have been removed. The back and forth movement of the slide latch is very slight as the door is opened and closed. Before the door is moved from wide open to closed position the operator manually raises the signal and holds it in position with notch 18 opposite the dog until the shoulder 8 moves the latch to seat the dog. The depth or extent of each shoulder 8 or 9 from a segment terminal to the adjacent side or edge of the casting is but slightly greater than the distance of the dog from a notch 17 or 18 in the retracted or forward position of the slide latch.

What is claimed is:

1. In a mail box, a body portion having one open end and flat side walls, a door, a hinge pin connecting said door and body, a right angle substantially triangular casting pivoted at its apex to said pin and connected to said door, the hypotenuse of said casting including a segmental portion having its terminals defined by straight shoulders, a flag signal adjustable vertically upon one of said flat side walls, guide brackets secured to said one flat side wall receiving the shank of said signal and supporting same in one signal position, said flag signal shank having spaced notches, a slide latch adjustable longitudinally of said one side wall operatively supported by said

5 guide brackets, a dog carried by said slide latch and movable into and out of said signal notches in predetermined relative positions of said flag signal as said slide latch moves back and forth along said one side wall, and a roller carried by said slide latch riding upon the segmental portion of said casting and engaged and actuated alternately by said straight shoulders to reciprocate said slide latch as said casting is moved back and forth through an arc of 90 degrees.

2. In a mail box, a body portion having one open end and flat side walls, a door movable through an arc of 90 degrees from open to closed position, a hinge pin connecting said door and body, spaced guide brackets secured to one of said side walls, a flag signal having a shank adjustably received in said guide brackets and in one position supported by one of said brackets, said flag signal shank having notched portions, a slide latch operatively supported by said guide brackets and engaging the shank of said flag signal, a dog carried by said slide latch movable into and out of the notched portions of said flag signal shank in predetermined positions of said signal, a roller at one end of said slide latch, and means made fast to one side of said door pivotally mounted to said hinge pin and movable with said door through an arc of 90 degrees to actuate said slide latch, said means including a segment struck from said hinge pin as a center and freely engaging said roller and shoulders defining said segment and alternately engaging and moving said roller and slide latch.
